UNITED STATES PATENT OFFICE.

AUSTIN C. LESCARBOURA, OF NEW YORK, N. Y., AND ALEXANDER RUSSELL BOND, OF PLAINFIELD, NEW JERSEY, ASSIGNEES TO THE AEOLIAN COMPANY, A CORPORATION OF CONNECTICUT.

MOUNTING FOR DIAPHRAGMS FOR ACOUSTICAL INSTRUMENTS.

Application filed November 5, 1918. Serial No. 261,281.

To all whom it may concern:

Be it known that we, AUSTIN C. LESCARBOURA, of the city of New York, in the county of New York and State of New York, and ALEXANDER RUSSELL BOND, of the city of Plainfield, in the county of Union and State of New Jersey, both citizens of the United States, have invented a new and useful Improvement in Mountings for 5 Diaphragms for Acoustical Instruments, of which the following is a full, clear, and exact 10 description.

Our invention relates particularly to diaphragms of phonographs, although it is 15 also applicable to other types of acoustical instruments in which diaphragms are used.

It is well known in the art of phonography that a diaphragm of small area or one whose natural period of vibration is high, will reproduce satisfactorily tones in the upper and intermediate ranges of the musical scale, but will not vibrate with sufficient amplitude to reproduce satisfactorily tones that are of low pitch. On the other hand a diaphragm of large diameter or one whose natural period of vibration is relatively low, while reproducing satisfactorily tones in the low and intermediate ranges of the musical scale, is too sluggish to reproduce high- 20 pitched tones. In some phonographic records it is more important to reproduce clearly and fully the high-pitched tones, while in others the reverse holds true. It is our purpose to provide a diaphragm 25 which can be adapted to reproduce clearly and fully either high-pitched tones or low-pitched tones.

Accordingly our invention provides a single diaphragm whose natural period of vibration can be varied at the will of the operator in order to adapt it to the reproduction of high-pitched tones or of low-pitched tones. Said variation of the period of vibration is effected by varying the "active area" of said diaphragm, and by "active area" we mean that part of the diaphragm that is vibrated or actuated by the reproducing stylus. Our invention also provides for variation of tension of said diaphragm in cases in which the material of which said diaphragm is composed has sufficient elasticity to permit of having its tension varied. When the tension is increased 50 the arrangement is such that the active area

of the diaphragm is simultaneously reduced, and vice versa, so that the variation in the diaphragm's natural period of vibration produced by variations of tension of said diaphragm compliment the variation in said diaphragm's natural period of vibration produced by varying the active area of said diaphragm. 55 60

With this and other objects in view our invention consists of novel features and parts and combinations of the same, as will 65 be more fully described hereinafter and then pointed out in our claims.

Reference is to be had to the accompanying drawing forming part of this specification, in which similar characters of reference indicate corresponding parts in all the figures. 70

Figure 1 is a front elevation of a phonograph sound box embodying our invention.

Figure 2 is a sectional view taken on the 75 line 1—1, Figure 1, viewed in the direction of the arrows.

Figure 3 is a view similar to Figure 2 in which, however, a diaphragm is shown with its active area reduced. 80

Figure 4 is a front elevation of a modification of our invention.

Figures 5 and 6 are sectional views taken on the line 4—4 of Figure 4, viewed in the direction of the arrows and showing the 85 diaphragm with its active area large and small, respectively, and Figure 7 is a side elevation of the sound box shown in Figure 4.

Referring to Figures 1, 2 and 3, A represents a casing of a sound box in which a diaphragm B is secured by means of a retaining ring C, said ring being held in place by means of screws D. The manner of securing said diaphragm may be varied 95 at will to conform with the best practice of the art and we wish it to be understood that we do not confine our invention to the specific method of securing the diaphragm which is shown in the accompanying drawings. Connected to the diaphragm B is a stylus bar E fulcrumed at F to the casing A and furnished with a stylus G adapted to bear on a phonograph record. The method of mounting the stylus bar is not an 100 essential feature of our invention and it will be readily apparent to any one versed in the art that the mounting of the stylus

bar could be altered so as to adapt our sound box for use with records which produce an axial vibration instead of a lateral vibration of the stylus, without interfering 5 with the mechanism we are about to describe for varying the active area of the diaphragm.

The casing A may be secured in any well-known manner to a tone arm H.

10 Within the casing A there is an annular flange I formed with a lip J. Said lip is virtually an annular fret against which the diaphragm B may be pressed by a ring K threaded into the retaining ring C, said 15 ring K being formed with a lip L registering with the lip J. The ring K is formed with lugs or finger pieces M to facilitate turning said ring.

When the parts are in the position indicated in Figures 1 and 2 the active area of 20 the diaphragm B is limited by the retaining ring C, but on turning the ring K clockwise the lip L impinges upon the diaphragm and bears it down upon the lip J. Between the 25 lips L and J the diaphragm is firmly gripped and thus the active area of the diaphragm is stopped off and bounded by lips L and J. When the parts are in the position indicated 30 in Figure 2 there should be sufficient clearance between the lips J and L and the diaphragm B to prevent said diaphragm from touching said lips when vibrated by the stylus G. Ring K may be threaded into ring D with a thread of such pitch that when said 35 ring K is turned through a partial rotation sufficient to bring the finger pieces M from the position shown in full lines to that shown by dotted lines in Figure 1, the diaphragm B will have been flexed to the position indicated 40 in Figure 3. At the same time the diaphragm B will be subjected to tension by the flexure produced by the pressure of ring K, thus further increasing the natural period of vibration of said diaphragm.

45 As diaphragms composed of certain materials are not adapted to be flexed to the extent required by the construction shown in Figures 1, 2 and 3, we have provided a modification shown in Figures 4 to 7 inclusive, in which the active area of a diaphragm can be varied without flexing said diaphragm.

In said modified construction A' represents a casing in which a diaphragm B' is 55 secured by means of a retaining ring C' held in place by means of screws D'. At E' is a stylus bar fulcrumed at F' in the usual manner and furnished with a stylus G' adapted to bear on a phonograph record. The casing A' is mounted on a tone arm H'. Threaded into the casing A' at the inner side 60 of the diaphragm is an annular member I' formed on its inner periphery with a lip J' adapted to be moved into engagement with 65 the diaphragm B'. On the opposite side of

said diaphragm there is another similar annular member K' formed with a lip L' and adapted to be moved into engagement with the diaphragm B' with said lip L' in registry with said lip J' but on the opposite 70 side of the diaphragm B'. Secured to member K' is a handle N projecting through a slot P in the retaining ring C' and secured to member I' is a similar handle O projecting through a slot Q in the casing A'. The 75 member K' is threaded into the ring C' with a right-handed thread while the member I' is threaded into the casing A' with a left-handed thread so that when the two handles N and O are moved from the position shown 80 in full lines in Figures 4 and 7 to a point R at which said handles are indicated by dotted lines in Figure 4 the members K' and I' will be moved one toward the other until they grip the diaphragm between them, as shown 85 in Figure 6. In the latter position the active area of the diaphragm is reduced without, however, imposing any tension upon said diaphragm.

It will be observed that slots P and Q extend beyond the point R at which the diaphragm is gripped when the two handles N and O are simultaneously moved to clamping position. The purpose of the extension of 90 said slots is to permit of placing said diaphragm under some tension if such tension be found desirable. If the handle N be moved down beyond the point R as indicated by dotted lines in Figure 7 the diaphragm B' will be flexed, and the degree of flexure is 95 dependent upon the extent to which said handle is moved beyond the point R. After said diaphragm is flexed as much as desired the handle O may be moved down until the lip J' clamps said diaphragm against the 100 member K'.

Having thus described our invention, what we claim as new and desire to secure by Letters Patent is:—

1. A mounting of the character described 110 comprising a vibratory diaphragm, means for supporting the same providing a normal vibrant pitch therefor, and means for varying the vibrant pitch thereof comprising a pair of diaphragm engaging members 115 of substantially equal diameter relatively movable into engagement with the opposite sides of the diaphragm to clamp the latter and to apply tension thereto.

2. A mounting of the character described 120 comprising a vibratory diaphragm, means for securing the periphery thereof and providing a normal vibrant pitch therefor, and opposed diaphragm engaging members normally disengaged from the diaphragm but 125 relatively movable into engagement with its opposite sides to clamp and displace the intermediate portion of the diaphragm laterally, thus subjecting the diaphragm to variant tension. 130

3. A mounting as characterized comprising a vibratory diaphragm, and a plurality of opposed clamping members adapted to flex the diaphragm out of its normal plane.
5. 4. A mounting as characterized comprising a vibratory diaphragm; means providing a boundry for determining the normal vibrant area of said diaphragm; and means for varying said area without subjecting 10 said diaphragm to tension, said latter means also being capable of subjecting said diaphragm to tension.
15. 5. In a mounting of the character described comprising a vibratory diaphragm having means for supporting its periphery in a normal plane, a plurality of opposed clamping members adapted to clamp the diaphragm between them and to flex the intermediate portion of the diaphragm out of said normal plane.
20. 6. The combination of a sound box, a diaphragm having means for supporting its periphery in a normal plane, and opposed clamping members at opposite sides of the 25 diaphragm and normally disengaged therefrom, said clamping members being relatively movable to clamp the diaphragm between them and to subject the diaphragm to a variant tension.
30. 7. In a mounting as characterized comprising a vibratory diaphragm, a plurality of opposed clamping members adapted to vary the normal vibrant area of said diaphragm while maintaining said diaphragm 35 in the normal plane thereof, said clamping members being operable at will to flex said diaphragm out of said normal plane.
40. 8. A diaphragm mounting comprising means for clamping the marginal area of the diaphragm and a pair of coacting clamping members of like contour, normally spaced from opposite faces of the dia-
- phragm but relatively movable into clamping engagement therewith to decrease the normal vibrant area of the diaphragm, 45 said clamping members being also operable to flex the diaphragm out of its normal plane.
9. The combination with a sound box and a diaphragm mounted therein, of gasket 50 members of substantially the same diameter adjustably supported at opposite sides of the diaphragm and means for shifting both said members either toward or away from the diaphragm, to clamp the diaphragm between them and disengage them from the diaphragm respectively and for flexing the diaphragm out of its normal plane.
10. A sound box comprising base and cover members having reversely screw-threaded seats, reversely threaded diaphragm-engaging members engaged with said seats and a diaphragm mounted in the sound box between said members.
11. The combination with a sound box 65 and a diaphragm mounted therein, of diaphragm-area reducing members mounted at opposite sides of the diaphragm and means for shifting both said members either toward or away from the diaphragm, said 70 members being capable of clamping the diaphragm to reduce its vibrant area without subjecting the diaphragm to tension and also capable of subjecting the diaphragm to tension.
75. In testimony whereof we have signed our names to this specification in the presence of two subscribing witnesses.
